SPINNING AND TWISTER RING

Ralph V. Blackwood, Lumberton, N. C.

Application April 21, 1949, Serial No. 88,810

1 Claim. (Cl. 57—112)

1

This invention relates to an improved yarn guide ring adapted to be mounted on a conventional ring rail of spinning frames, twisters and the like.

It is an object of this invention to provide a yarn guide apparatus for spinning frames, twisters and the like comprising an annular member or ring having a groove extending around its inner surface in which a ring is loosely mounted and to which yarn may be directed from a suitable source such as the drawing rolls of a spinning frame, the yarn passing between the outer periphery of the last-named ring and the bottom of the groove in which it is disposed and then extending to a rotating bobbin.

It is thus seen that the use of a traveler such as is normally employed in spinning rings, is eliminated.

It is another object of this invention to provide a ring for spinning frames and the like having upper and lower annular members having their inner proximate edges cut away, so that when they are placed in superposed relation a groove substantially semi-circular in cross section will be provided for loosely receiving a floating ring and having means for securing the upper and lower members together and also securing the upper and lower members to the ring rail of the spinning frame, and to further provide coinciding slots in the upper and lower members extending from the inner to the outer surfaces thereof and being disposed substantially tangent to the curvature of the inner surface of the upper and lower members and communicating with the groove in the inner surface of the upper and lower members to thus provide means for rapidly threading the yarn between the periphery of the second ring and the bottom of the groove in the inner face of the upper and lower members, it being understood that the ring rail should have a coinciding slot therein to facilitate passing the yarn through the slot in the ring during the threading operation.

Since a traveler is not employed in my improved spinning and twisting ring, it is seen that the use of a lubricant is eliminated and this also insures that the yarn, regardless of whether it is a wet or dry twist yarn, will be free of lubricant or stains which normally collect on the yarn as it passes through the traveler on other types of spinning and twister rings.

Some of the objects of the invention having been stated, other objects will appear as the description proceeds, when taken in connection with the accompanying drawings, in which—

2

Figure 1 is a front elevation showing a portion of a spinning frame and showing the improved ring applied to a portion of the ring rail and a bobbin extending therethrough;

5 Figure 2 is a sectional plan view taken along the line 2—2 in Figure 1;

Figure 3 is a vertical sectional and fragmentary view taken substantially along the line 3—3 in Figure 2 and showing the manner in which the 10 yarn engages the yarn guiding rings and is directed to the bobbin;

Figure 4 is an enlarged vertical sectional view of the right-hand portion of Figure 3;

Referring more specifically to the drawings the 15 numeral 10 indicates a bolster rail which supports a plurality of bolsters 11, only one of which is shown in the drawings. This bolster 11 rotatably supports a spindle 13 having a whorl 14 to which conventional driving means, not shown, are connected for transmitting rotation to the spindle 13. This spindle 13 has a bobbin 15 mounted thereon in which yarn 15 is adapted to be wound.

Disposed a substantial distance above the bolster rail 10 is a vertically movable ring rail 19 which is provided with a plurality of openings 20 only one of which is shown in the drawings. This ring rail 19 is driven by conventional means, not shown, to move up and down with respect to the bobbin 14 so as to lay the yarn 15 onto the bobbin evenly.

The numeral 21 broadly designates the ring as a whole which comprises upper and lower ring members 22 and 23 respectively. The proximate inner edges of each of the ring members 22 and 35 23 are provided with coinciding substantially quarter-circular grooves which, when the ring members 22 and 23 are assembled, form a groove 24 around the inner face of the ring 21 in Figures 3 and 4.

40 The upper and lower ring members 22 and 23 are secured together by bolts 26 which also secure the members 22 and 23 to the ring rail 19, the ring 21, of course, being positioned in cooperating alinement with the opening 20 in the ring rail 19.

45 The members 22 and 23 are provided with coinciding slots 27 which extend from the outer to the inner surfaces of the ring 21 and these coinciding slots 27 are disposed substantially tangent to the inner surface of the ring 21. In order to facilitate the threading of yarn through the coinciding slots 27 in the members 22 and 23 it is preferable that the ring rail 19 be provided with a plurality of slots 30, there being one slot 30 for each of the rings 21 and this slot 30 coincides with the slot 27 in the members 22 and 23.

Also, before the upper and lower members 22 and 23 are assembled in the manners shown in Figures 3 and 4, a continuous floating ring 31, of substantially less thickness than the width of the groove 24 and of substantially less overall diameter than the diameter of the groove 24, is mounted in the groove 24 between the members 22 and 23. It will be noted in Figures 3 and 4 that this floating ring 31 is of substantially the same inner diameter as the inside diameter of the members 22 and 23, however, the outside diameter of the ring 31 is substantially less than the diameter at the bottom of the groove 24 in the members 22 and 23 and is thus loosely confined within the groove 24. It is preferable that the outer peripheral edges of the ring 31 be rounded, as at 32, and that the ring 31 be polished to avoid breaking the yarn as it passes thereby. Also in Figure 4, it is preferred that the peripheral edge of the groove 24 at the upper member 22 be rounded as at 33 and that the inner surface of the member 22 be polished to further prevent the yarn from breaking as it passes thereby.

It is thus seen that upon placing an empty bobbin 14 on the spindle 13, an operator may thread the yarn through the coinciding slots 30 and 27 in the ring rail 19 and the guiding ring 21 and the yarn will then pass downwardly from a suitable source, such as the drawing rolls of a spinning frame, and will then engage the inner surface of the upper member 22 and pass into the groove 24 and around the outer periphery of the ring 31 and thus to the bobbin 14. The spindle 13 being driven, the yarn 15 is then wound about the bobbin 14 and, at the same time, the yarn 15 moves around the floating ring 31, the outer ring 21 remaining stationary.

In the drawings and specification there has been set forth a preferred embodiment of the in-

vention, and although specific terms are employed, they are used in a generic and descriptive sense only, and not for purposes of limitation, the scope of the invention being defined in the claim.

3 I claim:

Means for feeding yarn onto a rotating bobbin comprising upper and lower ring members each having upper and lower planar surfaces and surrounding the bobbin, a source of yarn, a ring rail, a plurality of bolts passing through the ring members and the ring rail to secure the planar members together and to secure them to the ring rail, said ring members having a continuous groove at their proximate inner edges, a floating ring loosely mounted in the groove formed in the upper and lower ring members, said ring rail having an opening coinciding with the upper and lower ring members, said upper and lower ring members and the ring rail having coinciding slots therethrough which are tangential to the inner surfaces of the upper and lower ring members, whereby yarn may be fed from the source through said slots into contact with the periphery of the floating ring, the lower inner edge of the uppermost of the ring members being rounded adjacent said groove to permit the yarn to pass thereby in engagement therewith to avoid breakage of the yarn.

RALPH V. BLACKWOOD.
